(57) **CLAIM**

The ornamental design for an electric furnace for substrate processing apparatus, as shown and described.

DESCRIPTION

FIG. 1 is a front, bottom and left side perspective view of an electric furnace for substrate processing apparatus showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof.

FIG. 8 is a cross-sectional view take along line 8-8 in FIG. 2 thereof; and,

FIG. 9 is an enlarged portion view taken along line 9-9 in FIG. 2.

In FIG. 8, the broken lines depict unclaimed subject matter only and form no part of the claimed design.

1 Claim, 8 Drawing Sheets
